UNITED STATES PATENT OFFICE.

THURE A. JOHANSON, OF ST. CHARLES, ILLINOIS, ASSIGNOR TO THE CABLE COMPANY,
OF CHICAGO, ILLINOIS, A CORPORATION OF ILLINOIS.

SOUNDING BOARD FOR PIANOS.

Application filed August 23, 1922. Serial No. 583,694.

This invention relates to piano construction, and more particularly to an improved method of constructing the piano sounding-board and supporting it upon the frame of the instrument.

As is well known to those acquainted with the general principles of modern piano construction, the arrangement of the piano strings must be such that the correct striking-point of each string will be properly positioned to receive the blow of the respective piano-hammer and, partly in order to meet this requirement and at the same time produce instruments as moderate in size as may be consistent with the provision of desired tonal characteristics, it has been customary to employ what is known as an "overstrung" arrangement of the strings.

In constructing an overstrung, upright piano, it is customary to provide it with a substantially rectangular sounding-board and to secure the edge-parts of the sounding-board upon "lining-strips" which are, in turn, secured upon the forward face of the "back" or frame of the instrument. Usually, the string-plate is secured directly in front of the sounding-board and the strings are arranged upon the plate so that the shorter treble strings are positioned adjacent the upper treble corner of the sounding-board, the longer strings of the treble section slanting downwardly slightly to the left from a position adjacent an upper intermediate portion of the sounding-board to a position between the lower middle portion and the lower bass corner thereof and the other strings of the treble section being arranged in graduated scale from the shorter to the longer strings. It is also usual to arrange the strings of the bass section so that they cross over in front of the longer strings of the treble section, extending downwardly to the right from a position adjacent the upper bass corner of the sounding-board to a position between the lower middle portion and the lower treble corner thereof. This overstrung arrangement of the strings with the consequent location of the sounding-board string-bridges does not, however, usu-

ally provide the proper allotment of effective sounding-board areas to the different strings of the scale, the result often being an unevenness of tonal quality and resonance.

The principal object of this invention is to improve the tonal characteristics of pianos of this type and, for this purpose, a novel sounding-board is provided, so constructed and supported that the various areas thereof which pertain to the respectively different strings of the scale will be more effectively and correctly apportioned thereto.

Another object of the invention is to provide a novel sounding-board support or "semi-cut-off" member, so arranged that it will effectively restrict the proper sounding-board areas pertaining to the shorter treble strings, provision being made against such restriction effecting an undesirable or improper lessening of the effective sounding-board areas pertaining to the overstrung strings of the bass section.

A further object of the invention is to provide a novel sounding-board "cut-off" member, so shaped and arranged that it will cooperate in correcting the apportionment of the sounding-board areas pertaining to the overstrung strings of the bass section.

Still further objects of the invention will appear from the detailed description to follow and from the appended claims.

In the drawings, in which an embodiment of the invention is shown—

Figure 1 is a rear view of an upright piano;

Fig. 2 is a front view of the string-plate, the sounding-board, and the "back" or frame of the instrument;

Fig. 3 is a section on the line 3—3 of Fig. 2; and

Fig. 4 is a section on the line 4—4 of Fig. 1.

Referring now to the drawings in detail, the piano construction shown therein comprises the "back" or frame 10; the sounding-board 11, mounted in front of said frame; and the string-plate 12, mounted in front of said sounding-board.

Broadly considered, the frame 10 may be of the usual construction employed in upright pianos, comprising the treble and bass side frame-members 13 and 14, respectively; a plurality of intermediately arranged frame-posts 15; and the upper and lower sets of filler-blocks 16 and 17, respectively, which are located between and firmly secured to the upper and lower end-parts of the frame-members 13 and 14 and of the several frame-posts 15.

Also, in a general way, the string-plate 12 may be of the usual construction employed in upright pianos, this string-plate being mounted in front of the sounding-board 11 and provided with an overstrung arrangement of the strings, the longer strings of the treble section 18 being crossed over by the strings of the bass section 19, as herein-before mentioned. Only a few of the strings of both sections are shown, in order to avoid obscuring other parts of the drawing.

A long curved bridge 20 is provided for the strings of the treble section 18, the string-plate 12 being designed to afford space for the proper location of this bridge upon the sounding-board to receive the bearing of the lower end-parts of such strings; and a comparatively short straight bridge 21 is provided for the strings of the bass section 19, the string-plate being cut away to afford an opening through which this bridge may extend to receive the bearing of the lower end-parts of the respective strings of this section. Both bridges are secured to the sounding-board and serve their well-known purposes.

It will be easily understood that the sounding-board areas pertaining to the shorter treble strings should be less in extent than those pertaining to the longer and heavier bass strings, and that the correct positioning of the sounding-board string-bridges within these areas is a most important factor in obtaining the properly responsive, vibratory action of the sounding-board.

Referring to Fig. 2, it will be observed that the treble bridge 20 extends downwardly and somewhat diagonally across the sounding-board from the upper treble corner portion thereof, and that the lower end of this bridge, as well as that of the bass bridge 21, is positioned very near the lower horizontal edge of the sounding-board. It is apparent that such an arrangement of the two bridges 20 and 21 does not provide a proportionate allotment of effective sounding-board areas for the different strings, nor does it provide a proportionate disposal of sounding-board areas upon opposite sides of either of the bridges. Usually, however, the diagonally opposite upper bass and lower treble corner portions of the sounding-board are dead-

ened by the arrangement, a cross said corner portions, of straight "cut-off" strips (not shown and not used in my improved construction), which are secured to the back of the sounding-board and to the frame. In many instances, these two corner portions of the sounding-board are actually cut off, the board terminating at the "cut-off" strips. While this employment of straight, diagonally arranged, cut-off strips materially reduces some of the sounding-board areas which should be reduced, it also reduces others which should not. In this regard, it may be observed that, in the construction shown herein, the upper bass corner cut-off member is peculiarly shaped, and no lower treble corner cut-off member is employed.

A curved support or semi-cut-off member 22 (which, as shown, may be formed of laminated strips of wood) is arranged to extend inwardly and downwardly a comparatively short distance across the back of the sounding-board from the lining-strip 23 which supports the treble edge-part thereof. This member 22 reaches across and is firmly secured upon the forward faces of the treble side frame-member 13 and the first treble frame-post 15. The forward face of member 22 is secured to the back of the sounding-board, but not for the full length of the member, the inner end-part of such forward face being cut away, as best shown at 24 in Fig. 4. The location, shape, and length of member 22 bear definite relation to the location and shape of the upper end-part of the treble bridge 20, a most important office of the member 22 being to effectively reserve the proper areas of the upper treble corner portion of the sounding-board (and particularly the areas lying just below the upper end-part of the treble bridge) for co-operation with the shorter strings of the treble section 18, cutting off therefrom the areas of the lower treble corner portion, which properly pertain to, and should be permitted to co-operate with, the longer and heavier overstrung strings of the bass section 19.

Attention is directed to the fact that, through the employment of the member 22, this invention provides for a practicable apportionment of the sounding-board areas pertaining to the shorter strings of the treble section 18 and of the areas pertaining to the overstrung strings of the bass section 19, and that such apportionment results in a more definite, intimate, and non-interfering association of such areas with the respective strings. Furthermore, through the employment of this member 22 and the described elimination of the usual lower treble corner cut-off strip, the location and restriction of these apportioned areas are such as to effect a more proportionate disposal thereof upon opposite sides of the bridges 20 and 21. In connection with this last statement, it should be noted that,

by doing away with the aforesaid usual cut-off strip for the lower treble corner portion of the sounding-board and utilizing the additional sounding-board areas thereby rendered available, and by restricting the areas of the upper treble corner portion of the sounding-board (by means of the member 22) from interference with the effectiveness of these additional areas, the areas pertaining to the overstrung strings of the bass section 19, and, in lesser degree, to the longer strings of the treble section 18 are, in a manner and in effect, moved downwardly to a location which is more in back of the bass bridge 21 and the lower end-part of the treble bridge 20.

It has been mentioned that the usual diagonal arrangement of straight cut-off strips is not entirely satisfactory and that the upper bass corner cut-off member herein shown is peculiarly shaped. This cut-off member 25 (which, as shown, may be formed of laminated strips of wood) is arranged in the form of a compound curve, the first portion 26 curving upwardly and inwardly a comparatively short distance across the back of the sounding-board from the lining-strip 27 which supports the bass edge-part thereof, and the second portion 28 curving upwardly in the reverse direction and then extending vertically upward to the lining-strip 29 which supports the upper edge-part of the sounding-board. The member 25 reaches across and is firmly secured upon the forward faces of the bass side frame-member 14 and the first bass frame-post 15. The forward face of member 25 is secured to the back of the sounding-board throughout the full length of the member, and it will be observed that the arrangement of the first portion 26 is such that it cuts off a considerable area of the upper bass corner portion of the sounding-board which would otherwise pertain to a few of the lower bass strings of the overstrung bass section 19, and that the upturned arrangement of the second portion 28 avoids reduction of the areas pertaining to the upper bass strings of the overstrung bass section 19 and does not interfere with the areas pertaining to the longer strings of the treble section 18. The location, shape, and disposal of the two portions 26 and 28 bear definite relation to the arrangement of the two sounding-board string-bridges 20 and 21 and to the hereinbefore described apportionment of the sounding-board areas located adjacent the lower treble corner portion thereof, the effect being to assist in accomplishing the hereinbefore mentioned proportionate disposal of sounding-board areas upon opposite sides of said bridges.

It may be mentioned that the usual sounding-board ribs 30, which are secured to the back of the board for stiffening pur-

poses, are continued through and secured to the members 22 and 25, the ribs being reduced considerably in thickness at the crossing-points (as at 31) and the forward faces of the members being notched (as at 32) deeply enough to receive such reduced portions of the ribs and facilitate firm attachment thereof, but not deeply enough to materially weaken the sounding-board-supporting qualities of the members.

Although it has been mentioned that the location, shape, and length of member 22 bear definite relation to the location and shape of the upper end-part of the treble bridge 20, and that the location, shape, and disposal of the two portions 26 and 28 of the member 25 bear definite relation to the arrangement of the two sounding-board string-bridges 20 and 21 and to the hereinbefore described apportionment of the sounding-board areas located adjacent the lower treble corner portion thereof, no attempt has been made to specifically describe these definite relationships, since this invention is not to be understood as depending upon, or limited to, any definitely stated location, shape, length, or disposal of these two members. The invention is applicable to pianos which differ greatly in the construction and relative arrangement of various parts which have to do with the determination of tonal characteristics and, in applying the invention to such instruments, the location, shape, length, and disposal of the said two members would have to be determined in accordance with such differences.

I claim as new and desire to secure by Letters Patent of the United States—

1. The combination, with a piano sounding-board having a string-bridge, of a sounding-board support extending partially and not entirely across said sounding-board, separating two adjoining active vibratory sounding-board areas which separately pertain to different portions of said string-bridge, and defining and apportioning the sounding-board area lying between said support and one portion of said string-bridge for vibratory co-operation with said one portion of said string-bridge.

2. The combination, with a piano sounding-board having a string-bridge, of a sounding-board support extending partially and not entirely across said sounding-board between two adjoining active vibratory areas thereof, defining the sounding-board area pertaining to one portion of said string-bridge and separating it from the sounding-board area pertaining to another portion of said string-bridge.

3. The combination, with a piano sounding-board having a first and a second string-bridge, of a sounding-board support extending upon said sounding-board between two adjoining active vibratory areas thereof which

separately pertain to said first and said second string-bridges, defining and apportioning the sounding-board area lying upon one side of said support between said support and one portion of said first string-bridge for vibratory co-operation with said one portion of said first string-bridge, and separating such sounding-board area from the sounding-board area lying upon the other side of said support and pertaining to said second string-bridge.

4. The combination, with a piano sounding-board having a first and a second string-bridge, of a sounding-board support extending upon said sounding-board between two adjoining active vibratory areas thereof which separately pertain to different portions of said first string-bridge and to said second string-bridge, defining and apportioning the sounding-board area lying upon one side of said support between said support and one portion of said first string-bridge for vibratory co-operation with said one portion of said first string-bridge, and separating such sounding-board area from the sounding-board area lying upon the other side of said support and pertaining to another portion of said first string-bridge and to said second string-bridge.

5. The combination, with a piano sounding-board having ribs and a string-bridge, of a sounding-board support extending across and bearing against certain of said ribs, separating two adjoining active vibratory sounding-board areas which separately pertain to different portions of said string-bridge, and defining and apportioning the sounding-board area supported by the ribs extending upon one side of said support for vibratory co-operation with one of said portions of said string-bridge.

6. The combination, with a piano sounding-board having ribs and a string-bridge, of a sounding-board support extending across and bearing against certain of said ribs between two adjoining active vibratory sounding-board areas, defining the sounding-board area pertaining to one portion of said string-bridge and supported by the ribs extending upon one side of said support and separating such sounding-board area from the sounding-board area pertaining to another portion of said string-bridge and supported by the ribs extending upon the other side of said support.

7. The combination, with a piano sounding-board having ribs and also having a first and a second string-bridge, of a sounding-board support extending across and bearing against certain of said ribs between two adjoining active vibratory sounding-board areas defining the sounding-board area pertaining to one portion of said string-bridge and supported by the ribs extending upon one side of said support, and

separating such sounding-board area from the sounding-board area pertaining to said second string-bridge and supported by the ribs extending upon the other side of said support.

8. The combination, with a piano sounding-board having a string-bridge, of a sounding-board support projecting inwardly upon said sounding-board from an edge-part thereof, diverging from a line parallel with a substantial portion of said string-bridge and terminating upon said sounding-board at the end of such inward projection thereupon; said support serving to define and apportion the sounding-board area lying between it and said portion of said string-bridge for vibratory co-operation with said portion.

9. The combination, with a piano sounding-board having a string-bridge, of a sounding-board support projecting inwardly upon said sounding-board from an edge-part thereof and between two adjoining active vibratory sounding-board areas, diverging from a line parallel with a substantial portion of said string-bridge and terminating upon said sounding-board at the end of such inward projection thereupon; said support serving to define and apportion the sounding-board area lying between it and said portion of said string-bridge for vibratory co-operation with said portion and to bar from such apportioned area interfering or conflicting vibratory action of the active sounding-board area lying upon the opposite side of said support.

10. The combination, with a substantially rectangular sounding-board having an obliquely arranged string-bridge, of a sounding-board support extending upon said sounding-board between two adjoining active vibratory areas thereof and terminating upon said sounding-board away from an edge-part thereof for barring from one end-portion only of said string-bridge the vibratory action of a substantial amount of the triangular area of said sounding-board lying upon one side of said string-bridge.

11. The combination, with a piano sounding-board having treble and bass string-bridges arranged thereupon, of a sounding-board support extending upon said sounding-board between two adjoining active vibratory areas thereof and terminating upon said sounding-board away from an edge-part thereof, whereby areas of said sounding-board pertaining to the bass string-bridge are separated from areas thereof pertaining to the treble string-bridge.

12. The combination, with the strings and sounding-board of a piano, of a sounding-board support extending inwardly upon and from an edge-part of said sounding-board between two adjoining active vibratory areas

- thereof and terminating upon said sounding-board away from said edge-part thereof, whereby areas of said sounding-board pertaining to certain of said strings nearer 5 said edge-part of said sounding-board are separated from areas thereof pertaining to others of said strings.
13. The combination, with the strings and sounding-board of a piano, and with the 10 sounding-board string-bridge for certain of said strings, which strings are of progressively increasing length, of means for apportioning for vibratory co-operation with a portion of said string-bridge the sounding-board areas lying adjacent to said portion and for barring the vibratory action of other active vibratory sounding-board areas therefrom; said means comprising a sounding-board support which extends upon said 15 sounding-board a portion only of the length of said string-bridge and terminates upon said sounding-board away from an edge-part thereof; said support-bar diverging throughout its extension upon said sounding-board from a line parallel with said portion of said string-bridge, whereby the 20 dimensions of the sounding-board areas apportioned as aforesaid progressively increase in approximate proportion to the progressively increasing length of said strings.
14. The combination, with a substantially rectangular sounding-board and a series of strings arranged to extend over the face thereof, of a sounding-board support extending upon said sounding-board between two adjoining active vibratory areas thereof and terminating upon said sounding-board away from an edge-part thereof for apportioning for vibratory co-operation 25 with certain of said strings the sounding-board areas of the corner-portion of said sounding-board which lie upon one side of said support and for barring from such apportioned areas interfering or conflicting vibratory action of other areas of said corner-portion of said sounding-board which lie upon the other side of said support, without barring the vibratory action of such other areas from others of said strings.
15. The combination, with the strings and sounding-board of a piano of the overstrung type, of a sounding-board support extending upon said sounding-board between two adjoining active vibratory areas thereof and terminating upon said sounding-board away from an edge-part thereof, whereby areas of said sounding-board pertaining to the overstrung strings are separated from areas thereof pertaining to other strings.
16. The combination, with the sounding-board and frame of a piano, said frame comprising two side-members and a member arranged therebetween to extend parallel with and nearer to one of said side-members, of a sounding-board support secured upon said 30 one of said side-members, extending across therefrom and secured upon said member, and terminating at the end of such extension; said sounding-board being secured about its edge-parts upon said frame and also secured to said support.
17. The combination, with the sounding-board and frame of a piano, said frame comprising two side-members and a member arranged therebetween to extend parallel with and nearer to one of said side-members, of a sounding-board support secured upon said one of said side-members, extending across therefrom and along upon said member, and terminating thereupon; said support being secured upon said member, and said sounding-board being secured about its edge-parts upon said frame and also secured to said support-bar.
18. The combination, with the sounding-board and frame of a piano, said frame comprising two side-members and two members arranged therebetween to extend parallel therewith, of a first sounding-board support secured upon one of said side-members, extending across therefrom and secured upon the nearest one of said two members, and terminating thereupon, and a second sounding-board support secured upon the other of said side-members, extending across therefrom and secured upon the other one of said two members, extending along and terminating thereupon; said sounding-board being secured about its edge-parts upon said frame and also secured to said first and second supports.
19. The combination, with the sounding-board and frame of a piano, said frame comprising two side-members and a member arranged therebetween to extend parallel with and nearer to one of said side-members, of a sounding-board support secured upon said one of said side-members, extending in a single curve across therefrom and secured upon said member, and terminating at the end of such curved extension; said sounding-board being secured about its edge-parts upon said frame and also secured to said support.
20. The combination, with the sounding-board and frame of a piano, said frame comprising two side-members and a member arranged therebetween to extend parallel with and nearer to one of said side-members, of a sounding-board support secured upon said one of said side-members, extending in a compound curve across therefrom and along upon said member, and terminating thereupon; said support being secured upon said member, and said sounding-board being secured about its edge-parts upon said frame and also secured to said support.
21. The combination, with the sounding-board and frame of a piano, said frame

comprising two side-members and two members arranged therebetween to extend parallel therewith, of a first sounding-board support secured upon one of said side-members, extending in a single curve across therefrom and secured upon the nearest one of said two members, and terminating thereupon at the end of such curved extension, and a second sounding-board support secured upon the other of said side-members, extending in a compound curve across therefrom and along upon the other one of said two members, and terminating thereupon; said sounding-board being secured about its edge-parts upon said frame and also secured to said first and second supports.

22. A piano construction comprising a sounding-board and having an overstrung system of strings, the bass strings crossing over the longer treble strings and extending therebeyond, whereby an angle is formed between such extension and the ends of the short treble strings, and said sounding-board having a portion in said angle not overlaid by either the bass or treble strings, in combination with a partial cut-off for the sounding-board lying in said angle adjacent the lower ends of the short treble strings, to make the effective sounding-board areas for the shorter treble strings approximately proportional to the lengths of said strings, said cut-off extending only a portion of the distance along the lower ends of the treble strings and terminating at the end of such extension, whereby the effective sounding-board area for the shorter treble strings is diminished without diminishing the effective sounding-board area for the bass strings.

23. A piano construction comprising a sounding-board and having an overstrung system of strings, the bass strings crossing over the longer treble strings and extending therebeyond, and said sounding-board having a portion overlaid by such extension of the bass strings but not overlaid by the treble strings, in combination with a cut-off for the sounding-board; said cut-off having a first portion overlaid by the extension of the bass strings and extending substantially transversely of the longer bass strings, and a second portion overlaid by said extension of the bass strings and extending obliquely with respect to the middle bass strings, whereby the effective sounding-board area for the longer bass strings is diminished without diminishing the effective sounding-board area for either the shorter bass strings or the longer treble strings.

24. A piano construction comprising a sounding-board and having an overstrung system of strings, the bass strings crossing over the longer treble strings and extending therebeyond on both sides, the extension on one side of the longer treble strings forming an angle with the ends of the shorter treble

strings, and said sounding-board having a portion lying in said angle not overlaid by either said bass or treble strings, in combination with a partial cut-off for the sounding-board lying in said angle adjacent the ends of the shorter treble strings, said cut-off extending only a portion of the distance along the lower ends of the treble strings, whereby the effective sounding-board area for the shorter treble strings is diminished without diminishing the effective sounding-board area for the bass strings, and a second cut-off for the sounding-board; said second cut-off comprising a first portion overlaid by the extension of the bass strings on the other side of the longer treble strings, and extending substantially transversely of the longer bass strings, and a second portion overlaid by said extension of the bass strings and extending obliquely with respect to the middle bass strings, whereby the effective sounding-board area for the lower bass strings is diminished without diminishing the effective sounding-board area for either the upper bass strings or the lower treble strings.

25. A piano construction comprising a substantially rectangular sounding-board and having an overstrung system of strings, the shorter treble strings overlying an upper corner portion of said sounding-board, the longer treble strings extending from the top to the bottom of said sounding-board, and the bass strings extending diagonally from adjacent the other upper corner to the lower middle portion of said sounding-board across the longer treble strings and extending therebeyond, in combination with a partial cut-off for the sounding-board running adjacent the lower ends of the shorter treble strings, to make the effective sounding-board areas for the shorter treble strings approximately proportional to the lengths of said strings, said cut-off extending only a portion of the distance along the lower ends of the treble strings and terminating at the end of such extension, whereby the effective sounding-board area for the shorter treble strings is diminished without diminishing the effective sounding-board area for the bass strings.

26. A piano construction comprising a substantially rectangular sounding-board and having an overstrung system of strings, the shorter treble strings overlying an upper corner portion of said sounding-board, the longer treble strings extending from the top to the bottom of the intermediate portion of said sounding-board, the bass strings extending diagonally from the lower middle portion of said sounding-board across the longer treble strings and extending therebeyond to a position adjacent the other upper corner of said sounding-board, in combination with a cut-off for said sounding-board, comprising a first portion overlaid by the extension

of the bass strings and extending substantially transversely of the longer bass strings, and a second portion overlaid by the extension of the bass strings and extend-

ing obliquely with respect to the shorter middle bass strings, whereby the effective sounding-board area for the longer bass

strings is diminished without diminishing the effective sounding-board area for either the shorter bass strings or the longer treble 10 strings.

In witness whereof, I have hereunto subscribed my name.

THURE A. JOHANSON.
